CLAIM

The ornamental design for a terminal display screen as shown and described.

DESCRIPTION

FIG. 1 is a front perspective view of a terminal display screen, showing our new design, according to a first embodiment;

FIG. 2 is a bottom, right rear perspective view thereof;

FIG. 3 is a top, left rear perspective view thereof;

FIG. 4 is a front view thereof;

FIG. 5 is a rear view thereof;

FIG. 6 is a left view thereof;

FIG. 7 is a right view thereof;

FIG. 8 is a top view thereof;

FIG. 9 is a bottom view thereof.

FIG. 10 is an enlarged view of portion 10 identified in FIG. 5.

FIG. 11 is a front perspective view of a terminal display screen, showing our new design, according to a second embodiment;

FIG. 12 is a bottom, right rear perspective view thereof;

FIG. 13 is a top, left rear perspective view thereof;

FIG. 14 is a front view thereof;

FIG. 15 is a rear view thereof;

FIG. 16 is a left view thereof;

FIG. 17 is a right view thereof;

FIG. 18 is a top view thereof; and

FIG. 19 is a bottom view thereof.

FIG. 20 is an enlarged view of portion 20 identified in FIG. 2.

FIG. 21 is an enlarged view of portion 21 identified in FIG. 2.

FIG. 22 is an enlarged view of portion 22 identified in FIG. 2.

FIG. 23 is an enlarged view of portion 23 identified in FIG. 3.

FIG. 24 is an enlarged view of portion 24 identified in FIG. 3.

FIG. 25 is an enlarged view of portion 25 identified in FIG. 3.

FIG. 26 is an enlarged view of portion 26 identified in FIG. 4.

FIG. 27 is an enlarged view of portion 27 identified in FIG. 5.

FIG. 28 is an enlarged view of portion 28 identified in FIG. 5;

FIG. 29 is an enlarged view of portion 29 identified in FIG. 5.

FIG. 30 is an enlarged view of portion 30 identified in FIG. 5.

FIG. 31 is an enlarged view of portion 31 identified in FIG. 7.

FIG. 32 is an enlarged view of portion 32 identified in FIG. 8.

FIG. 33 is an enlarged view of portion 33 identified in FIG. 9.

FIG. 34 is an enlarged view of portion 34 identified in FIG. 12.

FIG. 35 is an enlarged view of portion 35 identified in FIG. 12.

FIG. 36 is an enlarged view of portion 36 identified in FIG. 12.

FIG. 37 is an enlarged view of portion 37 identified in FIG. 12.

FIG. 38 is an enlarged view of portion 38 identified in FIG. 13.

FIG. 39 is an enlarged view of portion 39 identified in FIG. 13.

FIG. 40 is an enlarged view of portion 40 identified in FIG. 13.

FIG. 41 is an enlarged view of portion 41 identified in FIG. 14.

FIG. 42 is an enlarged view of portion 42 identified in FIG. 15.

FIG. 43 is an enlarged view of portion 43 identified in FIG. 15.

FIG. 44 is an enlarged view of portion 44 identified in FIG. 15.

FIG. 45 is an enlarged view of portion 45 identified in FIG. 15.

FIG. 46 is an enlarged view of portion 46 identified in FIG. 16.

FIG. 47 is an enlarged view of portion 47 identified in FIG. 16.

FIG. 48 is an enlarged view of portion 48 identified in FIG. 17.

FIG. 49 is an enlarged view of portion 49 identified in FIG. 18; and,

FIG. 50 is an enlarged view of portion 50 identified in FIG. 19.

The dash-dot broken lines, enclosing the detail views and enlarged views in FIGS. 2-5, 7-10 and 12-50, represent the extents of the views and form no part of the claimed design. All remaining even-dash broken lines represent portions of the terminal display screen that form no part of the claimed design.
